UNITED STATES PATENT OFFICE

LESTER M. WALDEN, OF CHICAGO, ILLINOIS

LINE-CASTING MACHINE

Application filed August 31, 1928. Serial No. 303,173.

The invention has general reference to line-casting machines of the type in which molten metal is forced through the mouth of a melting pot into a line mold, to form a slug. More particularly the invention relates to an attachment for cleaning and wiping the mouth of the melting pot after each casting operation to remove any foreign matter, such as metal drippings, dross or the like.

10 The object of the invention is to provide a new and improved attachment of this character which is under the direct control of the machine and which in its wiping contact with the mouth of the pot travels through a 15 vertical path lying substantially in the plane of the face of the mouthpiece of the melting pot.

A further object of the invention resides in the provision of a device of this character, 20 the movements of which are resiliently attained in the wiping direction and are positively effected by the movement of a machine part in the return direction thereby eliminating a forced wiping action liable to result in 25 damage to the mouthpiece or mold.

Another object is to provide a device of this character the movement of which is under the control of a suitable moving machine part to the end that such movement 30 is at a relatively slow constant speed as contradistinguished from a rapid snap action.

Other objects and advantages will become apparent in the following description and from the accompanying drawings, in which:

35 Figure 1 is a fragmentary side elevation of a part of a line-casting machine showing the invention incorporated therein.

Fig. 2 is a plan view of the part of the machine shown in Fig. 1, the view being 40 taken substantially along the lines 2—2 of Fig. 1.

Fig. 3 is a detail view of the rear side of the pad which wipes the mouthpiece.

45 Fig. 4 is a sectional view on an enlarged scale taken along the line 4—4 of Fig. 3.

Fig. 5 is a front elevation of a detail showing the mouthpiece of the melting pot with the wiping pad occupying the position 50 assumed at the end of a wiping stroke.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

For the purpose of illustration, the invention has been shown as being incorporated in a line-casting machine of the type known commercially to those skilled in the art, as 65 a linotype machine. During the cycle of operation of such machines a step occurs during which the flattened mouthpiece 10 of the melting pot 11 is advanced temporarily against the back of the mold 12, mounted 70 in a mold disk 13, to close the mold during which time molten metal is forcibly ejected from the mouthpiece into the mold to form a slug. Immediately after the slug is formed, the pot is retracted to its original position. 75 It has been found in practice that there is a tendency of molten metal, dross or other matter to accumulate upon the mouthpiece of the pot, which accumulation prevents the close contact of the mouth of the pot with 80 the mold in an ensuing casting operation.

During another step in the machine operation, the mold disk 13 moves forwardly to carry the mold to the slug trimming and ejecting position. This movement is effected 85 by means of a mold slide, generally indicated at 14, and provides, for a brief space of time, a relatively narrow space or clearance between the mouthpiece and the mold disk. Subsequently an ejector slide 14^a, 90 which is slidably mounted in the mold slide 14, moves forwardly while the mold disk is forward in its ejecting position to eject the slug from the mold. It is this movement of the ejector slide 14^a during the interval of 95 clearance between the mouthpiece and mold disk which I utilize in wiping the mouthpiece.

In accomplishing the objects therefore, I provide a swinging member rigidly mounted 100

on the frame of the machine and operably connected to the reciprocating ejector slide 14^a in such manner that the member sweeps vertically downwardly at a relatively slow steady speed across the mouthpiece immediately after the mold disk has been moved forwardly to provide the clearance between the disk and the mouthpiece.

One of the features of the invention resides in this vertical movement of the device. Customarily, the mouthpiece 10 includes an arrangement of transverse ports 10^a, through which metal is forced into the mold, alternating with a series of vertically extending vents 10^b, which permit air to escape from the mold as metal is injected thereinto. Metal or dross is apt to fill these ports and vents, interfering with the injection of metal and the escape of air to prevent efficient casting and a vertical wiping stroke, as embodied herein, is essential to clean the mouthpiece, and particularly the vertical vents, thoroughly of foreign matter.

Referring to Figs. 1 and 2, the device comprises a bracket member 15 arranged to be secured in any suitable manner, as by the bolt 16, to an appropriate part of the frame 17 of the machine. The bracket is provided with forwardly and rearwardly extending arms 18 and 19 which support a lever 20 and an actuating arm 21 respectively. The lever 20 carries the wiping member and is preferably in the form of a bell crank mounted on the bracket arm 18 by means of the pivot pin 22, with one arm 20^a thereof extending forwardly of the machine. For a purpose to be presently set forth a plate 30 is preferably formed integrally at the forward end of the arm 20^a and carries a bar 31 rigidly secured thereto and extending laterally therefrom in the direction of the mouthpiece.

The actuating arm 21 is also pivotally mounted intermediate its ends as by means of the pivot pin 23 upon the arm 19 of the bracket and has one end 21^a depending therefrom substantially into the path of the slide 14^a. A lug 24 projecting from the end of the depending arm 21^a is arranged to abut the rear face of the slide 14^a in the normal position thereof. The other end 21^b of the arm 21 is connected to the free end 20^b of the bell crank lever 20 by means of a suitable link 25 interposed therebetween. A spring 26 is connected at one end to a lug 27 on the link 25 and at the other end to a pin 28 rigidly mounted upon the bracket 15.

By this construction it will be seen that the spring 26 exerts a force which normally holds the forwardly extending arm of the lever 20 in its downward position and the depending end of the actuating arm 21 in its forward position abutting the slide 14^a.

The downward movement of the lever arm 20^a may be adjustably limited by such means

as an adjusting screw 37 carried by the arm for abutting engagement with the stop lug 38 on the bracket 15.

The preferred disposition of parts as determined by the location of the bracket on the frame, is such that when the ejector slide 14^a is in its inoperative or rearward position the rear face of the slide engages the lug 24 on the arm 21 to hold the arm in its rearward position. This position of the arm, through the link 25, maintains the forwardly extending arm 20^a of the lever 20 in raised position, as shown in dotted outline in Fig. 1. In consequence of this arrangement, as the ejector slide moves forwardly to push the slug from the mold, the arm 21^a follows the slide, permitting the spring 26 to move the lever arm 20^a downwardly toward the clearance formed between the mouthpiece and the mold disk when the mold disk was moved into the slug ejecting position.

The forwardly extending arm of the swinging lever 20 is substantially elongated and carries at its forward end a wiping member generally indicated at 29. The length of the arm is such that the wiping member, in swinging downwardly, describes an arc to which the surface of the mouthpiece is substantially tangential to pass freely through the clearance between the mold disk and the mouthpiece. However, since the arm is elongated the sweeping movement of the wiping member across the mouthpiece is in a substantially vertical path which is substantially in the plane of the face of the mouthpiece. This insures that portions of the wiping member will engage each of the parts and vents in the mouthpiece thoroughly to clean them of foreign matter.

In its preferred embodiment the wiping member 29 is detachable from the arm in order to permit of ready removal or replacement when the member becomes worn. Referring to Figs. 3, 4 and 5, the wiping member comprises an elongated pad 32 of suitable material, such as felt, which is detachably secured in a protecting shield 33, arranged to be mounted on the laterally extending bar 31. A preferred form of shield, as shown in Fig. 4, comprises a flat plate of a somewhat resilient metal, such as brass, bent at one end upon itself to provide a bar receiving loop 34. At spaced intervals along the length of the shield, portions thereof are cut away on three sides from the bottom of the loop to provide tabs 33^a. Substantially at the top of the loop the tabs are bent outwardly from the face of the shield to form a top portion of the loop, and thence are bent first away from the loop substantially parallel to the face of the shield as at 35 and then inwardly toward the shield to provide pad engaging points 36.

Thus the pad 32 may be secured to the shield 33 by the prongs 36 and as the bar 31 is in-

serted into the loops 34 the sides of the bar engage the unbent portions of the tabs 33^a to urge the points 36 into a substantially rigid clamping engagement with the pad 32. Preferably the shield 33 extends upwardly, as at 5 33^b, to form a guard above the pad, which portion is bent to overlie the pad thereby guarding the pad from accidental engagement with the upper edge of the mold disk in the return 10 movement of the arm.

In operation the device is mounted upon the frame of the machine with the arm 20 extending forwardly to position the wiping member 29 substantially in operating position. Final adjustment of the position of the wiper may be easily effected by forming the 15 pivot pins 22 and 23 eccentrically, in a well known manner, so that a slight rotation of the pins moves the wiper toward or from the mouth piece. The stop screw 37 is adjusted to permit the wiping member to swing downwardly a sufficient distance to just clear the metal openings 10^a and the air vents 10^b in the mouth piece.

The device is then adjusted for operation and in the normal position is held in a remote position above the melting pot by the abutment of the arm 21^a with the ejector slide 14^a. Movement of the slide forwardly gradually permits the spring 26 to pull the arm 20^a and the wiping member 29 downwardly across the mouthpiece, the swinging movement being controlled by the slide so that the movement of the wiping member between the 30 mold disk and the mouthpiece is completed 35 while the clearance therebetween is greatest. A return movement of the slide 14^a moves the arm 21^a rearwardly and swings the arm 20^a upwardly to its normal position.

It will be seen, that, by this construction, the downward movement of the wiper, is effected by the spring 26. Consequently, should the wiper, by misadjustment or accident, come into contact with the mouthpiece, 40 mold disk or other part of the machine the arm will be held by such contact against movement until released by the return movement of the slide. Furthermore, the return movement is positively actuated by the abutment of the slide with the arm thereby insuring that the wiping device will always be moved upwardly from its extreme position between the mouthpiece and the mold disk. Since each movement of the wiper is directly 45 controlled by the slide, such movements will be relatively slow. This is desirable since the wiping pad sometimes carries a slight amount of grease or graphite, and a rapid or snap movement, on occasion, would throw the 50 grease or graphite into the mold and onto the matrices, which, as those skilled in the art are aware, prevents good casting.

It is contemplated, that in certain instances the mold disk and the slides are moved forwardly manually to give access to parts of

the machine for cleaning or adjustment purposes. On such occasions it is desirable to retain the wiping device in its elevated, out of the way, position. This may be readily accomplished by providing a slidably mounted pin 39, (Fig. 2) at an appropriate point on the bracket arm 18 capable of being moved into the path of the lever arm 20^b to prevent movement of the wiping member downwardly. The pin 39 may be conveniently operated by such means as a wire 40 connected thereto.

I claim as my invention:

1. In combination with a line-casting machine having a part moving in a horizontal path through a definite operative cycle and a melting pot having a mouthpiece, a wiping member arranged for swinging movement across said mouthpiece, resilient means urging said member toward one position, and an operative connection between said member and said moving part positively holding said member in the opposite position against the force of said resilient means and releasable only when said part moves through its operative cycle.

2. In combination with a line-casting machine having a part moving through a definite operative cycle and a melting pot having a mouthpiece, a wiping member arranged for swinging movement across said mouthpiece in a vertical plane, resilient means connected to said wiping member urging said member downwardly, and linkage connected to said member and engaging said moving part to permit the resiliently actuated downward movement of said member as said part moves through one half of its cycle and to return said member against the force of the resilient means as the part completes its cycle.

3. A line-casting machine having, in combination, with a part of said machine movable through a definite operative cycle and a melting pot having a mouthpiece, a mouthpiece wiping device comprising an arm arranged for swinging movement in a vertical plane, a wiping pad carried by said arm and arranged for wiping contact with the mouthpiece during a part of said swinging movement, a lever engaging said operative part, and means including a spring connecting said arm and lever and tending to urge said arm downwardly and to maintain said lever in engagement with said part.

4. A line-casting machine having, in combination with a part of said machine movable through a definite operative cycle and a melting pot having a mouthpiece, a mouthpiece wiping device comprising an arm arranged for swinging movement in a vertical plane, a wiping pad carried by said arm and arranged for wiping contact with the mouthpiece during a part of said swinging movement, a lever having an abutting engagement with said operative part, means including a spring connecting said arm and lever and tending to

urge said arm downwardly and to maintain said lever in abutment with said part, and means limiting the downward movement of said arm.

5. A line-casting machine, having, in combination with a part of said machine movable through a definite operative cycle and a melting pot having a mouthpiece, a mouthpiece wiping device comprising an arm arranged for swinging movement in a vertical plane, a wiping pad carried by said arm and arranged for wiping contact with the mouthpiece during a part of said swinging movement, a lever having an abutting engagement with said operative part, means including a spring connecting said arm and lever and tending to urge said arm downwardly and to maintain said lever in abutment with said part, and means movable optionally into engaging position to hold said arm against downward movement.

6. In a wiping device of the character described, the combination of a supporting member and a wiping member, said wiping member comprising a body plate bent at one end to form a loop engageable by said supporting member, a wiping pad of fibrous material, and a plurality of pad engaging members formed integrally with said body plate to comprise a part of said loop, said engaging members being movable upon engagement with said supporting member into firm holding engagement with said pad.

7. In a wiping device of the character described, the combination of a supporting member and a wiping member, said wiping member comprising a fibrous pad, and means for mounting said pad on said supporting member including a plate engageable by said supporting member and means on said plate adapted to be held in clamping relation with said pad by the connection between said plate and said supporting member.

8. In a line-casting machine having a melting pot mouthpiece provided with elongated air-escape vents and a machine part having reciprocating movement a wiping member for said mouthpiece, and means operatively connecting said member to said machine part for movement of said member across said mouthpiece in a path substantially paralleling said vents.

In testimony whereof, I have hereunto affixed my signature.

55 LESTER M. WALDEN.
